UNITED STATES PATENT OFFICE.

HARRY THAYER KINGSBURY, OF KEENE, NEW HAMPSHIRE.

DESIGN FOR AN END PLATE FOR TOY COAL-CARS.

SPECIFICATION forming part of Design No. 31,102, dated June 27, 1899.

Application filed May 31, 1899. Serial No. 718,916. Term of patent 14 years.

To all whom it may concern:

Be it known that I, HARRY THAYER KINGSBURY, a citizen of the United States, residing at Keene, in the county of Cheshire, State of New Hampshire, have invented a certain new and original Design for an End Plate for Toy Coal-Cars, of which the following is a description, reference being had to the accompanying drawing and to the letters of reference marked thereon.

My invention relates to a new and original design for end plates for toy coal-cars; and it consists in an end plate of the shape and configuration herein described, and illustrated in the accompanying drawing, in which the figure represents a plan view of an end plate for toy coal-cars embodying my invention.

In the drawing, A represents the plate, which is shown as rectangular in general shape, but having projecting from each end ears *a a*, herein shown as two in number on each end.

Having thus described my invention, what I claim, and desire to secure by Letters Patent, is—

The design for an end plate for toy coal-cars; substantially as shown and described.

In testimony whereof I affix my signature in presence of two witnesses.

HARRY THAYER KINGSBURY.

Witnesses:

W. L. MASON,
C. L. STURTEVANT.
